W. H. BROWN.
DUMPING TUB.

No. 37,808.

Patented Mar. 3, 1863.

UNITED STATES PATENT OFFICE.

WILLIAM H. BROWN, OF ERIE, PENNSYLVANIA.

IMPROVEMENT IN DUMPING-TUBS.

Specification forming part of Letters Patent No. 37,808, dated March 3, 1863.

To all whom it may concern:

Be it known that I, WILLIAM H. BROWN, of Erie, in the county of Erie and State of Pennsylvania, have invented a new and useful Improvement in Skips or Dumping-Tubs; and I do hereby declare that the following is a full, clear, and exact description of the same, reference being had to the accompanying drawings, making a part of this specification, and to the letters of reference marked thereon.

This invention relates to handling ore, earth, coal, and other similar substances, and is used principally in connection with the apparatus for transporting, raising, lowering, and placing burdens, for which a patent was issued to me on the 2d day of January, 1855; but it may be used with ordinary derricks or cranes or other means of lifting and transportation.

The object of my invention is to discharge the material that is being handled from the tub in which it is transported with as little power specially applied to that purpose as may be possible and consistent with security; and it consists of a tub, or "skip," as it is technically called, in which the material is loaded and transported, and from which it is discharged by the action of gravity simply by releasing a catch or detent.

To enable others skilled in the art to make and use my invention, I will proceed to describe its construction and operation, with reference to the drawings, in which—

Figures 1 and 2 are respectively a partial end view and a side elevation of the same.

The skip or tub *a b c d* is hung upon the pivots *e*, placed on each of its two sides, by which it is suspended by the arms *f* from the cross-bar *g*. When the tub is empty, it hangs as shown by the continuous lines of the drawings, and it is held in that position by the vibrating bar *h*, which is hung on the pivot-bolts *i* on each side of the tub in such a way that the part passing around the back of the tub preponderates over the anterior part and rests upon the brackets *k*. The anterior ends of the vibrating bar *h* carry segments of a circle, *l*, into each of which is formed a slot for the reception of the pins *m*, secured in the arms *f*.

The position of the pivots *e*, by which the tub is hung, is determined by the positions of the respective centers of gravity of the mass when the tub is empty, and when it is filled, in such a manner that it will hang as described when it is empty, and will tilt over forward when the center of gravity has been raised by filling it full of earth, ore, or coal; and it discharges its contents by tilting, as described, and shown in dotted lines on the drawings, when the preponderating part of the vibrating bar *h* has been raised sufficiently to clear the slots of the segments *l* from the pins *m*, as is also shown by dotted lines, and permits the gravitation of the mass to operate independent of the restraint of the bar. The vibrating bar may be worked by hand when the tub has reached its destination, or it may be operated by a trip-line by which the tub may be dumped at any point desired.

The extent of the rotation of the tub in discharging its load is determined by the horns *n* striking the bars *f*. When the tub has been emptied, the preponderance of the bottom restores it to its normal position, in which it is held by the pins *m*, which slide over the segments and fall again into the slots therein, as above described.

The tub and the details of the arrangement for its suspension may be modified so as to present a different appearance from that shown in the drawings without departing from the principle of my invention, which consists in adjusting the point of suspension relatively to the centers of gravity in such a manner that the tub will be top up when empty and will be reversed when filled, subject to the condition, however, in this latter alternative, that it is not otherwise restrained.

I claim as my invention and desire to secure by Letters Patent—

The skip or tub, balanced and restrained substantially as described, and dumped when required, in the manner and for the purpose specified.

WM. H. BROWN.
